[57] CLAIM

The ornamental design for a bird feeder, as shown and
described.

DESCRIPTION

FIG. 1 is a perspective view taken from the top of a bird
feeder showing my new design;

FIG. 2 is a front elevational view thereof, the rear being
the same as the front shown;

FIG. 3 is a left side elevational view thereof, the right
side being the same as the left side shown;

FIG. 4 is a bottom plan view thereof; and

FIG. 5 is a top plan view thereof.
